UTILITY TEST LAMP

Chauncey H. Ribble, Hackensack, N. J., and Alexander J. Heidt, Woodhaven, N. Y.; said Heidt assignor to said Ribble

Application October 31, 1936, Serial No. 108,506
Renewed October 10, 1939

1 Claim. (Cl. 240—11.2)

This invention relates to utility test lamps, an object of the invention being to provide a unit of this character which permits tests of live wires, and which constitutes a shock-proof contact unit 5 designed to offer maximum safety and so constructed as to protect the lamp bulbs and filaments even though the unit is accidentally struck or dropped.

A further object is to provide a unit of this 10 character in which the lamp sockets and electric connections are embedded in a block of soft rubber, which is integral with the lamp housing or may be a separate part removable from the lamp housing.

15 With these and other objects in view, the invention consists in certain novel features of construction and combinations and arrangements of parts, all of which will be more fully herein-after described and pointed out in the claim.

20 In the accompanying drawings—

Fig. 1 is a view in longitudinal section illustrating one form of our improved utility test lamp;

Fig. 2 is a view in transverse section on the line 2—2 of Fig. 1;

25 Fig. 3 is a view similar to Fig. 1, illustrating a modification;

Fig. 4 is a view similar to Figs. 1 and 3, illustrating another modification;

Fig. 5 is a view in longitudinal transverse section on the line 5—5 of Fig. 4;

30 Fig. 6 is a view in transverse section on the line 6—6 of Fig. 4;

Fig. 7 is an end view of the electric connection removed from the casing; and

35 Fig. 8 is a view in elevation of the electric connections shown in Fig. 7.

Referring more particularly to Figs. 1 and 2 of the drawings, 10 represents a housing which is of soft rubber and molded into shape, providing an open lamp chamber 11 at one end defined by a wall 12 of suitable thickness and constituting an integral part of the housing. 13 represents what may be termed a base block, although in the preferred form of our invention this block 40 also constitutes an integral part of lamp housing. In this block 13 a pair of socket shells 14 are embedded and adapted to receive electric lamps 15 located in the chamber 11 and preferably in line with window openings 16 in opposite side walls of the housing. 17 represents a rubber cable which is projected into and has one end thereof embedded in the base of the housing, and 18, 19 and 20 are electric conductors projecting from the inner end of the cable and also 50 embedded in the base 13. A metal bar 21 is

5 embedded in the base 13 and is connected to electric terminals 22 and 23 on the shells 14. One of the conductors, 19, is connected to this bar 21 and the conductors 18 and 20 are connected to terminals 25 on the center contact of the shells 14, and these conductors 18, 19 and 20, at their other ends, are provided with testing prongs or other means for coupling the same to a source of electricity.

In manufacturing the unit, the shells 14 with 10 their terminals, the bar 21, the end of the cable 17, and the conductors 18, 19 and 20 are assembled and located in a mold, and rubber is then placed in the mold around these parts so that they are all embedded in the rubber of the housing. It is to be understood that this rubber is 15 of the soft type which will sustain any ordinary shocks to which it might be subjected.

In the modification illustrated in Fig. 3 of the drawings, a base block 26, corresponding to the base block 13 in the preferred form, constitutes a removable part and is separate from the housing 27. In this block 26 the same arrangement of shells, terminals, and other electric connections are embedded, and similar parts are given 25 the same reference characters in both forms of the invention. The housing 27 is provided on its inner face, preferably at its ends, with ribs 28, and the base block 26 is formed with grooves 29 to receive the ribs 28 and secure the base 30 block in the housing against accidental removal. However, to facilitate the removal of the base block, integral tabs 30 may be formed at the 35 ends thereof, which act as finger holds so they may be gripped to draw the base block out of the housing.

In the modification illustrated in Figs. 4 to 8, inclusive, we employ a soft rubber block or base 31 integral with the casing, and so shape the same as to permit the electric connections to be 40 removed therefrom or replaced therein and while these electric connections are in a very real sense embedded in the block when in normal position and protected and shielded by the cushioning of the soft rubber base, they are not 45 molded into the base or block as is the case with the forms of our invention heretofore described. In this modification the base 31 is formed with a longitudinal bore 32 to receive the cable 17, and it is also shaped to receive the 50 socket shells 14 and the conductors 18, 19 and 20. The bar 21 which is connected to the terminals 22 of the socket shell is movable through a slot 33 in the block or base 31, so that this 55 entire electric assemblage may be drawn out 55

of the base and returned to position therein after repair or replacement.

While we have used the term "embedded", it is to be understood that this term is used in its broadest sense to include the actual molding and adhering of the soft rubber to the electric connections or the shaping of such soft rubber block or base so as to receive, enclose, and house the electric connections therein, whether they 10 be permanent in the block or removable therefrom.

In the modification illustrated in Figs. 4 to 8 of the drawings, we have employed the same reference characters to indicate like parts as 15 those set forth in connection with the other figures.

While we have illustrated in all forms of our invention three electric conductors, it is obvious that one of these conductors may be omitted, as 20 for example the middle conductor 19, so that the invention is not limited to the particular number of conductors employed.

In the modifications, as well as in the preferred form, all parts of the housing, including 25 the base block, are of soft rubber and the elec-

tric conductors are housed or molded into and embedded in the soft rubber of the base block.

While we have illustrated and described what we believe to be preferred embodiments of our invention, it is obvious that various slight 5 changes may be made with regard to the form and arrangement of parts without departing from our invention, and hence we do not limit ourselves to the precise details set forth but consider ourselves at liberty to make such changes 10 and alterations as fairly fall within the spirit and scope of the claim.

We claim:

A utility test lamp including a housing formed with encircling walls presenting a lamp chamber 15 and a thickened apertured bottom formed with a pair of socket openings and a slot connecting said openings, a pair of socket shells, a bar connecting said shells, said bar and said shells being removably mounted in said socket openings and 20 said slot, and electric conductors operatively connected with said shells, said conductors extending through the aperture in said bottom.

CHAUNCEY H. RIBBLE.

ALEXANDER J. HEIDT. 25
